COMBINATION BRACKET

Filed Dec. 9, 1946

LUTHER P. JEFFREYS
INVENTOR.

BY Cecil L. Wood

ATTORNEY

UNITED STATES PATENT OFFICE

2,480,027

COMBINATION BRACKET

Luther P. Jeffreys, Fort Worth, Tex.

Application December 9, 1946, Serial No. 715,035

2 Claims. (Cl. 248—251)

1

This invention relates to hanging devices for window shades, curtains, drapes, and the like, and it has particular reference to a combination bracket capable of supporting a window shade and one or more curtain or drape rods, as set forth in a co-pending application filed by Luther P. Jeffreys on September 7, 1946, and bearing Serial No. 695,377, and its principal object resides in the provision of a new article of manufacture in which is embodied a design by which a combination bracket can be formed from a single strip of metal, such as aluminum, or other suitable material, in right- and left-hand units.

Another object of the invention resides in the provision of a compact and economical bracket unit fabricated with integral projections engageable by conventional types of curtain rods and arranged to accommodate a pair of such rods having identical dimensions and thereby obviate the necessity for providing different length rods ordinarily utilized in pairs and which require manufacturers and merchants to make and stock two sizes of rods in order to supply users of the conventional types of brackets.

The invention, therefore, broadly contemplates the provision of a simple integral arrangement capable of being shaped by stamping and forming processes with a minimum of operations.

While the foregoing objects are paramount, other and lesser objects will become manifest as the description proceeds, taken in connection with the appended drawings wherein:

Figure 1 illustrates the invention in perspective shown attached to a window header and having a shade roller and a pair of rods attached, the header, shade roller and rods being shown fragmentarily.

Figure 2 is an end elevational view of the invention.

Figure 3 is a vertical cross-section, taken on lines 3—3 of Figure 4, illustrating the preferred form of the rod supporting members.

Figure 4 is a plan view of the invention.

Figure 5 is an end elevational view of a modified form of the invention, showing a push-on type of rod supporting elements.

Figure 6 is a lateral cross-sectional illustration of the modified form of the invention, taken on lines 6—6 of Figure 7.

Figure 7 is a vertical sectional view of the modification shown in Figures 5 and 6, and illustrates the rod supporting members in elevation.

Figure 8 is a vertical cross-sectional illustration, taken on lines 8—8 of Figure 9, of another modification of the invention, and

2

Figure 9 is a plan view of the modification shown in Figure 8.

The invention accordingly comprises a unitary structure or stamping formed in right- and left-hand brackets from strips of metal and defining base portions 10 from which integral shade roller supports 11 and 12 extend rigidly at right angles. The shade roller support 11 has a conventionally formed notch 13 therein adapted to receive the tensioned shaft of a shade roller 14. The opposite roller support 12 has an aperture therein for the spindle 15 of the roller 14, as apparent in Figures 1 and 2.

The units are formed by a plurality of folds 15 in the material by which the shade roller supports 11 and 12, as well as the curtain rod supports 17 and 18, are formed. The oppositely arranged brackets each have a pair of rod brackets 17 and 18 spaced from the supports 11 and 12 20 and from each other, in the manner shown in Figures 1 and 4, and the members 17 are longer than the members 18. This arrangement provides for the attachment of rods 19 of the same dimensions and insures their proper spacing, as shown 25 in Figure 1.

Each of the rod support elements 17 and 18 are formed with notches *a* in their upper edges *b*, the rear sides *c* of these notches *a* being inclined upwardly and rearwardly, as especially apparent 30 in Figures 1 and 3. Thus is defined a stud 20 at the top and front of each of the members 17 and 18 receivable in slots 21 formed in the upper sides of the ends 22 of the rods 19, as shown in Figure 1. The rods 19 are of the conventional type.

The ends 22 of the rods 19 are secured to the studs 20 of the members 17 by the slots 21 in the upper portions thereof and the lower sides of the rods 19 bear against shoulders *d* defined on the 40 supporting member 17 by the depending portions *e*. It is desirable that the distance between the shoulders *d* and the outer ends of the members 17 be approximately that of the full length of the shorter elements 18 so that the body portions 23 of the rods 19 are properly spaced since the end portions 22 of both rods are of the same length.

The rods 19 are affixed to the shorter supports 18 in the same manner but the lower sides of the rods bear against a shoulder *f* required by a depending portion 24 which appears in Figure 3. Both sets of supports 17 and 18 have their lower forward edges *g* curved to expedite the attachment of the rods 19.

The modified structures, illustrated in Figures 55 to 9, inclusive, are formed in the same manner

as the preferred structure, shown in Figures 1 to 4, but their rod supporting elements 25 and 26 have straight upper and lower edges so that the rods 19 can be applied by simply pushing their ends 22 over the elements 25 and 26 for a frictional association therewith. These members may be formed with embossing 27 to provide frictional contacts with the rods 19 and more securely retain the same in position on their mountings.

It is also desirable to form the brackets with perforated mounting tabs 28 on each side of the support arrangements by which the invention can be attached to the header 29 and forms a part of the base 10.

The invention is unique in its manner of construction, being formed in a plurality of closely pressed folds by a stamping process, and it is obvious that certain changes in design may be resorted to from time to time without departing from the spirit and intent of the invention or the scope of the appended claims.

I claim:

1. In a combination right- and left-hand bracket for window shades and curtains, an integral unit formed from a single strip of metal and forming a mounting base having a shade roller support extending at right angles there-

from, a pair of spaced curtain rod supports formed in folds of said strip arranged parallel to and spaced from said roller support in said base, one of said rod supports having the greater length whereby a pair of curtain rods of identical dimensions can be supported on said bracket and properly spaced horizontally.

2. In a new article of manufacture, a combination right- and left-hand window shade and curtain rod bracket formed integral from a single strip of metal, said bracket being formed in folds defining an attaching base having a shade roller support and a plurality of curtain rod supports arranged at right angles to said base and in spaced relationship, the said curtain rod brackets having different lengths whereby to horizontally space a pair of rods of identical dimensions.

LUTHER P. JEFFREYS.
